INVENTOR

WALTER I. CHAPMAN
BY
John H. Chapman
ATTORNEY

UNITED STATES PATENT OFFICE.

WALTER I. CHAPMAN, OF JERSEY CITY, NEW JERSEY.

ROOFING-TILE AND FASTENING MEANS THEREFOR.

1,353,807.

Specification of Letters Patent. Patented Sept. 21, 1920.

Application filed April 23, 1918. Serial No. 230,241.

To all whom it may concern:

Be it known that I, WALTER I. CHAPMAN, a citizen of the United States, and resident of Jersey City, in the county of Hudson and State of New Jersey, have invented certain new and useful Improvements in Roofing-Tiles and Fastening Means Therefor, of which the following is a specification.

The subject matter of this invention is a roofing tile of the type which is usually composed of reinforced concrete, Portland cement or the like and is made of sufficient size and otherwise adapted to be placed directly upon and fastened to the purlins.

The primary object of my invention is to produce a tile having fastening means secured to and coöperating with the under side of the overlapping portion of a tile to provide a socketed seat, open at its rear end, and adapted to receive and form a joint with the underlying portion of an adjacent tile and also to engage the purlin and fasten the tiles thereto.

Another feature of my invention comprises the provision at opposite ends of each tile of coöperating, fastening and alining means of novel form whereby the ends of adjacent tiles may be interlocked and alined with each other and simultaneously fastened to the purlins.

Another feature of my invention comprises the provision of a plurality of nuts embedded in the bottom surface of the overlapping portion of the tile and means coöperating therewith and preferably comprising a Z-shaped clip, for engaging the end of the adjacent tile and fastening both ends to the purlin.

Other objects will be in part obvious from the annexed drawing and in part indicated in connection therewith by the following analysis of this invention.

This invention accordingly also consists in the features of construction, combinations of parts and in the unique relationships of members and in the relative proportioning and disposition thereof, all as more completely outlined herein and in the said drawings.

To enable others skilled in the art so fully to comprehend the underlying features

of this invention that they may embody the same by numerous modifications in structure and relation contemplated thereby, drawings depicting preferred forms have been annexed as a part of this disclosure and in the drawings like characters of reference denote corresponding parts throughout all the views of which—

Figure 1, is a plan view of a plurality of tiles fastened together as employed in roofing;

Fig. 2, is a longitudinal section through tiles embodying my invention showing the same fastened to the purlins;

Fig. 3, is a plan view of the under side of a tile embodying my invention;

Fig. 4, is a transverse section on the line 4—4 of Fig. 1;

Fig. 5, is a perspective view of my preferred form of clip;

Fig. 6, is an enlarged view of separated fragments of a tile illustrating interlocking relationship thereof, and Fig. 7, is an enlarged section of a modified form of clip and connection embodying my invention.

Referring now to Figs. 1 to 6 of these drawings, each of the tiles 1, has secured to it beneath its overlapping marginal portion 2, one or more fastening devices 4, which coöperate with the under face of the said overlap to form a socketed seat, preferably open at its rear end, for the reception of the underlying marginal portion 3 of an adjacent tile. The fastening device 4, as shown, comprises a clip Z-shaped in conformation and is secured to the under face of the marginal overlap or contiguous portion by means of a nut 5, embedded in the cementsitious material from which the tile is formed. The nut 5 extends only to the under-surface of the tile so as to leave the upper face thereof free from holes, which would prevent the formation of a tight joint, and meshes with a screw 6, which as shown is passed through a hole 7 in a flange 8, abutting against the under side of the said tile. The intermediate portion 9 of the clip 4, extends at right angles to the under face of the said overlap and a flange portion 10 extends rearwardly therefrom to form with said underface of the overlap a socketed seat

for the reception of the underlying portion of an adjacent tile. This flange 10 preferably has a downward inclination with respect to said under face of the overlap so as 5 to permit a resilient engagement between it and the under face of the said underlying portion of the adjacent tile and the flange 11^a of a purlin 11, to which the tiles are secured.

10 Each tile has an underlying marginal portion 3, which is preferably provided with notches 12 in vertical alinement with the fastening devices 4. These notches are adapted to be engaged by and interlocked 15 with the fastening devices 4, the intermediate portions 9, of the two fastening devices 4 entering the notches 12, while the flange 10 bears against the under face of the underlying portion and the inclination of the 20 flange 10 permits it to take under the flange of the purlin so as to secure the tiles thereto.

A kerf 13 is formed transversely along the under face of the overlapping portion of the tile and this kerf is filled with plastic 25 cement or the like, to assist in the formation of a water tight joint.

The tiles may be laid substantially in the conventional manner, *i. e.* the bottom row first and the next row having the clips 30 secured thereto will be slid over the top edge of the said bottom row so that the intermediate portions of the fastening devices or clips will enter the notches and the free flange portion will bear against the 35 under surface of the underlying portion of the first row and furthermore will engage beneath the flange of the purlin.

In the modified form of device shown in Fig. 7, instead of providing a Z-shaped clip, 40 the shank 14 of a bolt 15, enters and interlocks with the notches 12, while a plate 16 has a hole 17, through which the bolt extends and said plate bears against the under face of the underlying marginal portion and 45 engages beneath the flange of the purlin.

In laying tile, having fastening devices of the character last above described, it is desirable to have a man stationed below the purlins for the purpose of interlocking the 50 bolts with the notches and screwing the same home to cause the plates 16 to bear against the under face of the tiles and the flange of the purlins.

The tiles 1, are also preferably provided 55 with the usual longitudinally-disposed rib 18^a, at one edge, a roll 18 coöperating with the rib of an adjacent tile, and with an intermediate roll 19, or the like, for the purpose of embracing the coöperating ribs and 60 rolls at the overlapping portions thereof.

Plastic cement or like material may be inserted between the rolls and ribs to assist in forming a tight joint.

Having described my invention, I claim:

65 1. A tile having a marginal portion at its

lower end adapted to form an overlap and a marginal portion at its upper end adapted to underlie an overlapping portion of an adjacent tile; fastening means secured to the under side of said overlapping tile and co-operating with the said marginal overlap to form a socketed seat for the reception of the underlying portion of an adjacent tile; and notches in the upper edge of the underlying portion adapted to interlock with the 70 fastening means on the overlapping portion of an adjacent tile.

2. A tile having a marginal portion at its lower end adapted to form an overlap and a marginal portion at its upper end 80 adapted to underlie an overlapping portion of an adjacent tile and fastening means comprising a nut embedded in the under surface of the tile, a clip spaced from said under surface of the overlap to form a 85 socketed seat for the reception of the upper marginal underlying portion of an adjacent tile, and a screw coöperating with said embedded nut for varying the width of said socket and fastening the tiles in place. 90

3. A tile having a marginal portion at its lower end adapted to form an overlap and a marginal portion at its upper end adapted to underlie an overlapping portion of an adjacent tile and fastening means 95 comprising a nut embedded in the under surface of the tile, a Z-shaped clip, having a flange spaced from said under face to form a socketed seat for the reception of the upper marginal underlying portion of an adjacent 100 tile, and a screw coöperating with said embedded nut for varying the width of said socket and fastening the tiles in place.

4. A tile having a marginal portion at its lower end adapted to form an overlap 105 and a marginal portion at its upper end adapted to underlie an overlapping portion of an adjacent tile, a plurality of nuts embedded in said tile and projecting to the under surface only, a plurality of fastening 110 clips each secured at one end to one of the said nuts and having its other end free and extending rearwardly to form a socketed seat open at its rear end for the reception of the upper underlying portion of an adjacent tile, and screws coöperating with said embedded nut for varying the width of said socket and fastening the tiles in place. 115

5. The combination with a purlin having a laterally-projecting flange, of a tile having 120 a marginal portion at its lower end adapted to form an overlap and a marginal portion at its upper end adapted to underlie an overlapping portion of an adjacent tile and abut against said purlin flange, a nut embedded 125 in said first mentioned tile and projecting to the under surface only, a fastening clip secured at one end to the said nut and having its other end free and inclining downwardly to form a socketed seat open at its 130

rear end and adapted to resiliently bear against the under face of the underlying portion of an adjacent tile and also to engage the said abutting flange of the purlin,
5 and a screw for applying pressure on said clip to fasten the tiles to said purlin.

Signed at the borough of Manhattan, city

of New York in the county of New York
and State of New York this day of April
5 A. D. 1918.

WALTER I. CHAPMAN.
